UNITED STATES PATENT OFFICE.

MORITZ MAYER, OF NEW YORK, N. Y.

SWINGING SIGN.

1,089,143.

Specification of Letters Patent. Patented Mar. 3, 1914.

Application filed September 19, 1913. Serial No. 790,642.

To all whom it may concern:

Be it known that I, MORITZ MAYER, a citizen of the United States, residing in the borough of Manhattan, city, county, and State of New York, have invented an Improvement in Swinging Signs, of which the following is a specification.

My present invention relates to signs, and particularly to swinging advertising signs, and the object thereof is the provision of a sign adapted to swing and to be returned and normally maintained in a position at right angles to that of the wall or partition on which the sign is placed.

In carrying out my invention, the sign, preferably made of sheet metal of any desired configuration, is suitably secured to a support which is mounted in a vertical position on a wall or similar place, and is provided with yielding means by which the sheet metal sign is returned and normally maintained in a position at right angles to the wall, it being possible by varying pressure, such, for instance, as the action of the wind, when the sign is placed out of doors, for the sign to be caused to swing and to be kept in motion continuously, so long as a varying pressure is exerted thereon, as will be hereinafter more particularly described.

In the drawing, Figure 1 is a perspective view of the sign embodying my present invention. Fig. 2 is a plan view of the same, showing in dotted lines various positions which the sign may assume in swinging.

Referring particularly to the drawing, my present invention comprises a sign, indicated at 10, which I have illustrated as the head and bust of a man, with a space beneath the same for advertising matter, although, as will be understood, the shape or configuration of the sign forms no part of the invention. Along one edge, the sign 10 is rolled, as indicated at 11, so as to receive a rod or standard 12, to which the sign is secured. The lower end of the rod 12, in the use of the sign, is placed in a socket 13, which is suitably secured to a wall or partition, indicated at 14. The upper end of the rod 12 is preferably passed through an

eye 15, which is also secured in the wall 14. The upper end of the rolled portion 11 of the sign terminates at a point appreciably distant from the upper edge of the sign proper, and between the upper end of the rolled portion 11 and the upper edge of the sign surrounding the rod 12, I employ a pair of springs: One of these springs is indicated at 16, and one end thereof is extended, as indicated at 17, and adapted to bear against the wall 14. The opposite end 18 of this spring 16 is also extended and passed through an aperture 19 in the sign 10. Similarly the spring, indicated at 20, has one end, indicated at 21, extended so as to bear against the wall 14 and the opposite end 22 is extended and passed through the aperture 19 in the sign. The springs 16 and 20 are of substantially equal strength, and being applied, as hereinbefore described, to exert pressure in opposite directions against the sign, will, as will be understood, normally maintain the sign in position at right angles to the wall or partition by which it is supported. Also, as will be understood, when the sign is moved, from being acted upon by an intermittent pressure of the hand or the variable action of the wind, the sign will swing and continue swinging so long as an intermittent or varying pressure is exerted, eventually, after the pressure has been removed, returning to its normal position at right angles to the wall.

I claim as my invention:

1. A sign comprising a sheet metal form, a standard to which the sheet metal form is secured, means for pivotally mounting the standard on a support, and yielding means for exerting equal forces in opposite directions against the said form to normally maintain the same in a position of rest at right angles to the face of the support, and to cause the sheet metal form to swing back and forth, when pressure has been exerted on either side thereof and after said pressure has been removed, until it returns to the said position of rest.

2. A sign comprising a sheet metal form, a rod to which at one side the sheet metal

form is secured, bearings in which the rod is mounted adjacent its ends, the said bearings being secured to a support, and springs surrounding the upper portion of the said rod, one end of each of the said springs bearing against the said support while the other ends of the said springs are passed from opposite sides through an aperture in the said

sheet metal form and bear upon the opposite sides thereof.

16

Signed by me this 13th day of September, 1913.

MORITZ MAYER.
